FIG. 1.

FIG. 2.

INVENTOR

MINNIE KNIGHT

BY Hazard & Miller

ATT'YS.

UNITED STATES PATENT OFFICE.

MINNIE KNIGHT, OF LOS ANGELES, CALIFORNIA, ASSIGNOR OF ONE-HALF TO CLARENCE W. DORLON, OF LOS ANGELES, CALIFORNIA.

DESIGN FOR A DOLL.

60,689.

Specification for Design.

Patented Mar. 21, 1922.

Application filed December 14, 1921. Serial No. 522,414. Term of patent 3½ years.

To all whom it may concern:

Be it known that I, MINNIE KNIGHT, a citizen of the United States, residing at Los Angeles, in the county of Los Angeles and State of California, have invented a new, original, and ornamental Design for a Doll, of which the following is a specification, reference being had to the accompanying drawing, forming a part thereof.

Fig. 2 is a rear view thereof.

I claim:

The ornamental design for a doll as shown.

MINNIE KNIGHT.
